METHOD FOR PRODUCING LUBRICATING OIL

Ulric B. Bray, Los Angeles, Calif., assignor to
Union Oil Company of California, Los Angeles,
Calif., a corporation of California

No Drawing. Application March 7, 1932,
Serial No. 597,419

19 Claims. (Cl. 196—13)

This invention relates to a process for the production of lubricating oil. More specifically, it relates to a process for the production of lubricating oil from crude oil containing asphalt and is a continuation in part of my application, Serial No. 466,189, filed July 7, 1930.

The value of oils as lubricants depends, to a large extent, upon their viscosity-temperature susceptibility, that is, their rate of change in viscosity with a change in temperature. Superior lubricating oils exhibit a low viscosity temperature susceptibility. By careful selection of crude stock, lubricants can be produced which exhibit a low viscosity temperature susceptibility. Lubricants made from residues of Pennsylvania paraffin base crude oil are of this class; however, the supply of this superior crude stock is limited and it, therefore, becomes necessary to obtain lubricants from other sources.

In the aforesaid application filed by me, I have shown that the lubricating oil components of most crude oil contain asphalt or asphalt and wax and are of a mixed character. Some of the constituents present have a high viscosity temperature susceptibility and in this respect resemble the ordinary commercial type of lubricating oil made from distillates of asphalt base crude oil. Furthermore, I have also pointed out that most asphalt base crude oils contain certain heavy lubricating oil components which upon isolation from the crude oil exhibit a low viscosity temperature susceptibility. In ordinary refinery practice these heavy lubricating oil components of the crude oil are left in the asphalt and do not find their way into finished lubricants. In case they are distilled overhead they lose their valuable viscosity characteristics and become highly susceptible to a change in viscosity with a change in temperature. This impairment in the viscosity characteristics of the heavy oils, appears to become even more pronounced when the distillation is carried out in the presence of asphalt.

Furthermore, in order to evaluate oils according to their temperature viscosity susceptibility characteristics, lubricants which exhibit a low

temperature viscosity susceptibility, such as Pennsylvania paraffin base lubricating oils, are described as having 100% paraffin base characteristics; lubricating oils produced from distillates of asphaltic crude oil by the ordinary commercial processes and which exhibit a high temperature viscosity susceptibility are described as having 0% paraffin base characteristics, and lubricating oils which exhibit temperature viscosity susceptibility characteristics intermediate between Pennsylvania lubricating oil and lubricating oil produced from asphalt distillates are evaluated according to the extent by which their temperature viscosity susceptibilities resemble the Pennsylvania paraffin base lubricating oil.

This is best shown by the ratio of the intercepts of the viscosity temperature curves of the paraffin base lubricating oil and the lubricating oil produced from asphaltic oil distillate with the oil having viscosity temperature susceptibilities intermediate between the two foregoing standard comparison oils.

I have also shown that crude oils which contain asphalt can be distilled to a certain point beyond which any further distillation will impair the viscosity temperature characteristics of the heavy oils in the asphaltic residue. Furthermore, I have shown that by distilling an asphaltic crude oil to a point below which any impairment in the viscosity temperature characteristics of the oil in the residue takes place and then separating the oil and asphalt in the residue by the use of certain solvents that I am able to obtain an oil which exhibits a low viscosity temperature susceptibility.

Furthermore, in the aforementioned application filed by me it was pointed out that oils which have been deprived of their asphalt content can be distilled to a point at which heavier overhead fractions are obtained without any substantial impairment of the viscosity temperature susceptibility of the heavy oils in the still residue than is possible where the distillation of the oil is carried out in the presence of the asphalt.

60 Table 1 shows the effect of distilling oil in the presence of asphalt. Temperatures above 600° F. are shown to be highly injurious to the paraffin base characteristics of the overhead oil.

60 characteristics. The absence of the asphalt during the distillation results in the preservation of the low viscosity susceptibilities possessed by the heavy oils present in the still residue.

65 Table 2 shows the effect of distilling oil which has been deprived of its asphaltic content by solvent extraction. From the data given in this table it is obvious that no substantial lowering of the paraffin base characteristics of the overhead fractions has taken place at 700° F. Furthermore, it is safe to say that the distillation of the asphalt free oil can be continued to a temperature of 750° F. without any substantial impairment of the paraffin base characteristics of the overhead oil.

65 It is, therefore, an object of my present invention to produce lubricating oil from oil containing asphalt by separating the asphalt from the oil and then separating the oil by distillation into its light and heavy components.

70 It is another object of my invention to produce lubricating oil from oil containing asphalt by first separating most or all of the asphalt from the oil by the aid of a solvent and then separating the light oil fractions from the heavy residual

70

75

lubricating oil fractions by fractional distillation.

It is another object of my invention to produce lubricating oil from oil containing asphalt by separating the asphalt from the oil by the aid of a solvent and then to distill the substantially asphalt free oil into a distillate and a residuum, interrupting the distillation at a point below which there is any substantial impairment of the temperature viscosity susceptibility of the residual oil.

As means of separating the asphalt from the oil, I may employ solvents or chemicals. Thus, I may employ such solvents as alcohol, mixtures of alcohol and ether, acetone or volatile hydrocarbon solvents, such as casinghead gasoline and light naphthas. I find, however, that the process is best carried out by the use of hydrocarbons which are normally in the vapor state at atmospheric pressure and temperature. Such hydrocarbons include propane, isobutane, butane, ethane, methane and mixtures thereof. These may be obtained by rectification of casinghead gasoline by the so-called "stabilizing method", now conventional in the natural gas industry, 25 they are the overhead thus obtained. They are liquefied by compression and cooling in the conventional manner and drawn off into pressure chambers where they are maintained in a liquid state until they are used. A typical analysis of such a fraction is 6.72% ethane, 72.20% propane, 30 19.91% isobutane and 1.17% normal butane. The pressure necessary to maintain such a fraction in the liquid state is approximately 125 pounds per square inch at 73° F. In future discussions such a solvent will be referred to as 35 "propane". It will be understood, however, that the term "propane" will cover other light volatile hydrocarbon mixtures in which the percentage of propane predominates similar to the one 40 shown above.

By extracting the asphaltic oil with a solvent capable of separating the asphalt from the oil and then distilling the oil to remove the light fractions, I am able to obtain an asphalt free 45 heavy oil residue having a low viscosity temperature susceptibility which may be employed as a superior lubricant. The removal of the asphalt prior to the distillation permits the separation of heavier oil fractions as distillates from the asphalt free oil without an impairment of viscosity characteristics of the oil remaining in the still.

In carrying out my invention other means may be employed to separate the asphalt from the oil prior to the distillation step. Thus the asphaltic oil may first be treated with sulphuric acid to separate the asphalt present after which the asphalt free oil may be distilled to separate the light oil fractions present away from the 55 residual oil which possesses a low viscosity temperature susceptibility. Other chemicals may also be employed to separate the asphalt from the oil, as for example, the metallic halides. The oil containing asphalt is treated with a metallic 60 halide at a temperature sufficiently high to coagulate the asphalt present. The coagulated asphalt is allowed to settle out and the asphalt free oil is decanted away from the coagulated asphalt and distilled to remove the light oil fractions from the residual oil.

In some cases it is desirable to employ both solvent extraction and chemical means to separate the asphalt from the oil prior to the distillation of the oil for the separation of the light oil fractions from the valuable residual lubricants.

Thus I may first commingle the asphaltic oil with a light hydrocarbon solvent, such as propane, to cause the major portion of the asphalt to precipitate out. After removing the precipitated asphalt from the light hydrocarbon solution of oil the latter may be further purified to remove any remaining undesirable bodies by treatment with sulfuric acid. The asphalt free and acid treated oil may then be distilled to remove the light hydrocarbon solvent and oil fractions from the heavy oils present which are characterized by exhibiting a low viscosity temperature susceptibility.

In my prior case, Serial No. 466,189, filed July 7, 1930, as has already been explained, I first 15 topped the oil to a definite point for the removal of the light fractions after which the asphaltic residue was extracted with a light liquid hydrocarbon, such as liquid propane, to separate the asphalt from the oil. The topping operation was 20 discontinued at the point below which any substantial impairment in the viscosity temperature characteristics had taken place. In most cases this limiting point in the topping operation is attained when the still temperature reaches 650° F.; 25 or where the viscosity of the oil on stream has reached approximately 500 seconds Saybolt Universal at 100° F. In my present method of operation in which I remove the major portion of the asphalt before separating the oil into a light overhead fraction and a heavy residual fraction exhibiting a low viscosity temperature susceptibility I find that I may continue the distillation of the asphalt free oil until a still temperature of 30 35 40 45 50 55 60 65 70 75 80 85 90 95 100 105 110 115 120 125 130 135 distilling crude oil to an on stream viscosity of approximately 500 seconds Saybolt Universal at 100° F., separating most of the asphalt from the remaining residue and subsequently distilling the 5 remaining residue at a temperature not exceeding 750° F. to produce a lubricating oil distillate and a residual undistilled lubricating oil, said temperature being insufficient to impair the temperature viscosity susceptibility of said lubricating oil distillate and said residual undistilled lubricating oil.

3. A process for the production of lubricating oil from oils containing asphalt which comprises distilling crude oil to an on stream viscosity of 15 approximately 500 seconds Saybolt Universal at 100° F., separating most of the asphalt from the remaining residue and subsequently distilling the remaining residue to an on stream viscosity not exceeding 1200 seconds Saybolt Universal at 100° 20 to produce a lubricating oil distillate and a residual undistilled lubricating oil.

4. A process for the production of lubricating oil from oils containing asphalt which comprises subjecting crude oil to a topping operation at a 25 temperature not substantially in excess of 650° F. to remove the lighter fractions therefrom, commingling the residue with an agent capable of removing substantially all of the asphalt from said residue, removing asphalt from said residue and 30 subsequently distilling the remaining residue at a temperature not in excess of 750° F. to produce a lubricating oil distillate and a residual undistilled lubricating oil, said last mentioned temperature being insufficient to substantially impair the temperature viscosity susceptibility of said lubricating oil distillate and said residual undistilled lubricating oil.

5. A process for the production of lubricating oil from oils containing asphalt which comprises 40 subjecting crude oil to a topping operation at a temperature not substantially in excess of 650° F. to remove the lighter fractions therefrom, commingling the residue with a solvent capable of 45 dissolving the oil and precipitating the asphalt, separating the solvent solution of oil from the precipitated asphalt, separating the solvent from the oil and subsequently distilling said asphalt-free residue at a temperature not in excess of 750° F. to produce a lubricating oil distillate and a 50 residual undistilled lubricating oil, said last mentioned temperature being insufficient to substantially impair the temperature viscosity susceptibility of said lubricating oil distillate and said residual undistilled lubricating oil.

55 6. A process as in claim 5 in which the solvent comprises a light liquid hydrocarbon.

7. A process as in claim 5 in which the solvent comprises a liquefied normally gaseous hydrocarbon.

60 8. A process as in claim 5 in which the solvent comprises liquid propane.

9. A process for the production of lubricating oil from oil containing asphalt which comprises 65 distilling crude oil to an on stream viscosity of approximately 500 seconds Saybolt Universal at 100° F., separating substantially all of the asphalt from the residue and subsequently distilling the substantially asphalt-free residue at a temperature not in excess of substantially 750° F. to produce 70 a lubricating oil distillate and a residual undistilled lubricating oil.

10. A process for the production of lubricating oil from oils containing asphalt which comprises distilling crude oil to an on stream viscosity of

approximately 500 seconds Saybolt Universal at 100° F., separating substantially all of the asphalt from the residue and subsequently distilling said asphalt-free residual oil to an on stream viscosity not exceeding 1200 seconds Saybolt Universal at 100° F. to produce overhead lubricating oil fractions and a residual undistilled lubricating oil.

11. A process for the production of lubricating oil from oils containing asphalt which comprises distilling crude oil to an on stream viscosity of 10 approximately 500 seconds Saybolt Universal at 100° F., commingling the residue with an agent capable of removing substantially all of the asphalt from said residue and removing the asphalt from said residue and subsequently distilling said asphalt-free residual oil to an on stream viscosity not exceeding 1200 seconds Saybolt Universal at 100° F.

12. A process for the production of lubricating oil from oils containing asphalt which comprises distilling crude oil to an on stream viscosity of 20 approximately 500 seconds Saybolt Universal at 100° F., commingling the residue with a solvent capable of dissolving the oil and precipitating the asphalt, separating the solvent solution of 25 oil from the precipitated asphalt, separating the solvent from the oil and subsequently distilling said asphalt-free residual oil to an on stream viscosity not exceeding 1200 seconds Saybolt Universal at 100° F.

13. A process for the production of lubricating oil from oil containing asphalt which comprises distilling crude oil to an on stream viscosity of 30 approximately 500 seconds Saybolt Universal at 100° F., commingling the residue with a liquefied 35 normally gaseous hydrocarbon solvent to dissolve the oil and precipitate the asphalt, separating the solvent solution of oil from the precipitated asphalt, separating the solvent from the oil and subsequently distilling said asphalt-free residual 40 oil to an on stream viscosity not exceeding 1200 seconds Saybolt Universal at 100° F.

14. A process for the production of lubricating oil from oils containing asphalt which comprises distilling crude oil to an on stream viscosity of 45 approximately 500 seconds Saybolt Universal at 100° F., commingling the residue with liquid propane to dissolve the oil and precipitate the asphalt, separating the propane solution of oil 50 from the precipitated asphalt, separating the propane from the oil and subsequently distilling said asphalt-free residual oil to an on stream viscosity not exceeding 1200 seconds Saybolt Universal at 100° F.

15. A process for the production of lubricating oil from oils containing asphalt which comprises 55 separating substantially all of the asphalt contained in crude oil and subsequently subjecting the asphalt-free crude oil to a distillation at a temperature not in excess of 750° F. to produce lubricating oil distillates and a residual undistilled lubricating oil.

16. A process for the production of lubricating oil from oils containing asphalt which comprises 65 commingling crude oil with an agent capable of removing substantially all of the asphalt from said crude oil, and subsequently distilling said asphalt-free oil to produce overhead lubricating oil fractions and a residual undistilled lubricating 70 oil, said distillation being accomplished at a temperature not substantially in excess of 750° F.

17. A process for the production of lubricating oil from oils containing asphalt which comprises commingling crude oil with a light liquid hydro- 75

carbon which is capable of dissolving the oil but not the asphalt, separating the undissolved asphalt from the solvent solution of oil, separating the solvent from the oil and subsequently distilling said asphalt-free oil to an on stream viscosity not exceeding 1200 seconds Saybolt Universal at 100° F. to produce lubricating oil distillates and an undistilled substantially asphalt-free residual oil.

18. A process as in claim 17 in which the light liquid hydrocarbon comprises a liquefied normally gaseous hydrocarbon.

19. A process as in claim 17 in which the light liquid hydrocarbon comprises liquid propane. 5
